UNITED STATES PATENT OFFICE.

FRANK LUCCINO, OF WATKINS, NEW YORK.

INVISIBLY-STITCHED SEAM AND METHOD OF MAKING SAME.

Application filed January 14, 1924. Serial No. 685,945.

To all whom it may concern:

Be it known that I, FRANK LUCCINO, a citizen of the United States, residing at Watkins, in the county of Schuyler and State of New York, have invented a new and useful Improvement in Invisibly-Stitched Seams and Methods of Making Same, of which the following is a specification.

10 This invention relates to an improved seam for joining the edges of leather parts, or parts formed of analogous material, and the method of producing such seam.

In the manufacture of certain kinds of goods, as for instance athletic boots or shoes which are sometimes formed of relatively heavy, soft leather, it is desirable that some, at least, of the seams by which the parts of the shoe are joined, be as smooth and uniform as possible for the comfort of the wearer, and also that the stitches be protected from rough usage and consequent breaking, which would result in weakening and opening of the seam. It should be understood that seams formed in accordance with this invention may be used in the manufacture of other articles or goods, and other materials having the characteristics of leather could be equally well employed, and the term "leather" throughout the specification and claims is intended to include such materials.

One object of the invention is to provide an improved concealed stitch seam for joining together the edges of leather or the like parts in which the edges may be brought together and secured by stitches which are entirely concealed between the faces of the material; also to so form the seam that it will be flush with the adjacent surfaces of the material, thus forming a neat and comfortable article, also the seam will be strong and durable and can be formed in a simple and practical manner.

Another object of the invention is to improve the methods of making seams of the sort mentioned.

In the accompanying drawings:

Fig. 1 is a plan view of a leather blank, from which a shoe upper is to be formed, and showing the same with a plurality of notches, the edges of which have been prepared for the reception of the stitching whereby these edges are secured together to form the improved invisibly stitched seams by the method embodied in this invention.

Fig. 2 is an enlarged plan view of a portion thereof.

Fig. 3 is a similar view showing the portion of the blank after the concealed stitches have been introduced and the edges of the part brought together thereby in producing the seam.

Fig. 4 is a transverse section thereof on line 4-4, Fig. 2.

Fig. 5 is a similar view on line 5-5, Fig. 3.

Fig. 6 is a similar view of the completed invisibly stitched seam.

For the purpose of illustrating the practical application of the invention a flat blank A of leather or the like is shown in the drawings, which is adapted to be shaped to form a one-piece upper for a shoe. The blank is formed with the usual ankle opening a and is further provided with a number of V-shaped notches or openings 10 around the edge, formed by cutting away small portions of the material. The opposite edges 11 of the openings are adapted to be brought together so as to abut and be secured to form seams so that the blank A will be shaped substantially in the form of an upper. It should be understood, however, that, instead of the single piece of leather shown, the upper could be formed of separate pieces joined on lines extending inwardly from the angles of the notches, thereby enabling small pieces of scrap leather to be utilized.

To form the invisibly stitched seam in accordance with the preferred embodiment of the invention, the leather adjacent the opposite edges 11 of each of the notches 10 is so prepared that stitches may be taken in the body or substance of the leather, adjacent the edges 11, such that when the edges are brought together so as to abut, the stitches will be embedded or concealed in the leather between the two faces 12, 12^a thereof. For this purpose, as shown clearly in Figs. 2 and 4, a channel or oblique cut 13 is made in one face of the leather adjacent each edge to be seamed, and preferably in such a way that the bottom 14 of each cut will be substantially parallel with and adjacent the edge, and preferably midway between the faces 12, 12^a, see Fig. 4. In this way a flap or free portion 15 is formed, the free edge of which is adapted to be lifted to expose the bottom 14 of the cut. Thus a groove is formed, such that, if the edges 11

are now brought together so as to abut, they may be secured together as by stitches 16, (see Figs. 3 and 5) in such a way that these stitches will extend substantially parallel with the faces 12, 12^a. As the bottoms 14 of the channels are readily accessible by lifting the flaps 15, the stitches 16 may be easily formed so as to extend back and forth from the bottom of one channel 10 to the bottom of the other channel across the meeting edges 11. After the stitches 16 have been made as described, the flaps 15 may be cemented or otherwise secured in their original positions so as to lie flat and 15 flush with the face of the leather in which the channels 13 are formed (see Fig. 6). When the flaps 15 have been so secured, the stitches 16 will be invisible from either face 12 or 12^a and as the edges 11 are drawn 20 tightly together the stitches will also be invisible at the finished seam 17. Furthermore, as the stitches are entirely embedded in the leather between its two faces they will be protected from any surface wear 25 incident to the use of the parts or articles in which they are formed.

It will be obvious from the foregoing description that the invisibly stitched seam may be readily used to connect together 30 any two or more pieces of leather or the like, having sufficient thickness to permit the channels to be formed, and such that the stitches may be readily extended through the leather between its faces. The seam 35 described provides an economical and practical means of connection, whereby leather parts, intended to be subjected to considerable wear, may be strongly stitched, while the stitches are protected from the 40 wear by being embedded between the faces of the leather.

I claim as my invention:

1. In an invisibly stitched seam for connecting two parts of leather or the like, 45 an inclined channel adjacent the contacting portions of each part, said channels being formed so as to leave the contacting portions uncut and the bottoms of said channels extending substantially parallel 50 to the line of contact, stitches passing from the bottom of one channel to the bottom of the other channel and drawing said parts together, said stitches extending away from the open ends of said channels through the 55 uncut material of each part from the bottom of each channel towards the bottom of the opposite channel.

2. In an invisibly stitched seam for connecting two parts of leather or the like, 60 an inclined channel formed in the face of each part adjacent the contacting portions of said parts, and stitches passing from the bottom of each channel to the bottom of the other channel in a direction away from the open ends of said channels and through 65

the uncut contacting portions of said parts so as to draw said parts together, said stitches being thus concealed in the leather between the outer faces of said parts.

3. In an invisibly stitched seam for connecting two parts of leather or the like, an inclined channel adjacent the contacting portions of each part, a flap on one face of each of said parts formed by cutting said channels, stitches passing from the bottom of each channel to the bottom of the other channel and drawing said parts together, said flaps being adapted to be secured to the portions from which they were cut, after said stitches have been made, to 70 conceal said stitches in the leather between the opposite faces of said parts and provide a seam which lies flush with said faces. 75

4. In an invisibly stitched seam for connecting two parts of leather or the like and 80 of substantially the same thickness, and having edges which are adapted to abut, an inclined channel adjacent said edges formed in one face of each of said parts, and stitches passing from the bottom of 85 each channel to the bottom of the other channel to draw said abutting edges together, said stitches extending through the uncut edge portions of said parts between the faces of said parts. 90

5. In an invisibly stitched seam for connecting two parts of leather or the like and of substantially the same thickness, and having edges which are adapted to abut, an inclined channel adjacent each of said edges, the bottom of said channels extending substantially parallel to said edges, a flap on a face of each part formed by cutting said channels, each of said flaps extending away from the adjacent edge of the part of which it is a portion, and 100 stitches extending from the bottom of each channel in a direction opposite to the flaps and passing to the bottom of the other channel through said abutting edges and between the opposite faces of said parts, 110 said flaps being adapted to be secured to the portions from which they were cut to conceal said stitches, said abutting edges and said flaps being so secured that said seam will be flush with the opposite faces of said connected parts. 115

6. The herein described method of forming an invisibly stitched seam for connecting two parts of leather or the like, which consists in forming an inclined channel adjacent the contacting portions of each part and so as to leave a flap extending away from the line of contact, and passing 120 stitches from the bottom of one channel to the bottom of the other channel in a direction away from the open ends of said channels so that said stitches will extend through the uncut and contacting portions of said parts, and then closing said channels, 125

whereby said stitches are concealed in the material of said contacting parts between faces thereof.

7. The herein described method of forming an invisibly stitched seam for connecting two parts of leather or the like and of substantially the same thickness, and having edges which are adapted to abut, which consists in forming an inclined channel adjacent each of said abutting edges so that the bottoms of the channels extend substantially parallel with said abutting edges and

lie in planes substantially midway between the opposite faces of said parts, passing stitches from the bottom of each of said channels to the bottom of the other channel so that said stitches extend substantially parallel with and between the opposite faces of said parts in a direction away from the open ends of said channels, and closing said channels to conceal said stitches in the material of said contacting parts. 15 20

FRANK LUPPINO.
